UNITED STATES PATENT OFFICE.

JOSEPH HOUSTON BROWN, OF MOORESVILLE, NORTH CAROLINA.

WELL-TILING COUPLER.

SPECIFICATION forming part of Letters Patent No. 529,776, dated November 27, 1894.

Application filed June 12, 1894. Serial No. 514,333. (No model.)

To all whom it may concern:

Be it known that I, JOSEPH HOUSTON BROWN, a citizen of the United States, residing at Mooresville, in the county of Iredell and State of North Carolina, have invented certain new and useful Improvements in Well-Tiling Couplers, of which the following specification contains a full, clear, and exact description, reference being had to the accompanying drawings, forming a part of this specification, in which—

Figure 1, is a longitudinal vertical section of the improved coupler with the first section of tiling thereon and in the act of being released. Fig. 2, is a similar view showing the coupler lowering one tile upon another and about to release it, the disk C² being removed. Fig. 3, is a transverse horizontal section through the coupler on line 3—3 Fig. 1.

My invention relates to that class of well-tiling couplers in which shouldered springs and suspension and releasing devices are employed for successively lowering the tiling or tubing into a bored well to form the lining thereof.

The object of the invention is to provide such a tubing or tiling coupler which shall be simple in construction and which will automatically release all tiles or tubes after the first one has been lowered in place.

A further object is to prevent accidental releasing of a tile or tube in its descent; also to prevent chipping or marring the edges of the tiles or tubes when the coupler is lowered into contact therewith.

My invention consists in the construction and combination of parts hereinafter described and specifically pointed out in the claims.

A, represents a cylindrical block which forms the body of the coupler. This block gradually increases in diameter from its upper to its lower end and is provided with external longitudinal grooves A', the lower portions of which are made deeper as shown at a'. The upper ends of the grooves A' merge into short transverse grooves A² on the top of the block.

B, are spring arms of greater length than the block and extending through the grooves A' therein; the upper ends of the arms being bent inwardly at right angles as at B' to fit

within the grooves A² and thus hold the spring arms and block against separating longitudinally when the block is drawn upwardly. A band A³ encircles the upper end of the block A and firmly binds the spring arms in the upper ends of the grooves A' which leaves them free to spring in and out in the lower deeper portions of the grooves. These spring arms incline slightly outward from the deeper portions of the grooves as shown at b and are about flush with the outer face of the lower wider end of the block A so that they may be compressed into said grooves. Each spring arm B is bent outwardly near its lower end to form a shoulder B² on which the lower end of the tile or tube may rest, and from this shoulder the arm extends downwardly and inwardly on a curve or at an incline as shown at B³. The block A has a central suspension eye A⁴ to which a chain or cord a⁴ may be attached for raising or lowering the coupler.

C, is a rod extending through a longitudinal bore c in the block and has a rack C' on one side of its upper end for engagement with a spring catch c', and the rod is connected between its ends by links c² with the lower extremities of the spring arms B. The lower end of the rod C is reduced and threaded, and on its threaded end is placed the removable disk C² which is held in place by a nut as shown. The links c² permit the spring arms to expand to their utmost limit at their lower shouldered ends, but will draw said arms inwardly when the rod C is pushed upwardly by the disk on its lower end striking the bottom of the well.

The block A is provided near its lower end with a series of radial pins A⁵ which space it from the interior of the tiling or tubing.

From the foregoing it will be seen that when a section of tiling or tubing is passed over the block A it will rest (as shown in dotted lines Fig. 1) upon the shoulders B² which form a firm support for it, and as the lower ends of the arms B are merely linked loosely together, they cannot be simultaneously pressed inwardly to accidentally release the tiling even though one of them should strike some obstruction in the bore of the well.

When the first tiling section is lowered to the bottom of the well the rod C will be pushed inwardly by its disk C² and the spring arms

will be drawn toward each other till their shoulders are removed from the lower edge of the tiling which will then remain in the well while the coupler will then be withdrawn by 5 the cord a^4 . In sliding upwardly the teeth on the rod C will successsively slide past the latch but the latch will prevent a return movement and hence the rod C will be locked and the spring arms held in their retracted position 10 while the coupler is being withdrawn. After the coupler has been withdrawn the disk C^2 will be removed. All the succeeding tiles will be lowered in the same manner, but as each one nears the one beneath, the lower 15 curved or inclined ends B^3 will enter therein and be automatically contracted to release the tiling from the shoulders. If the lower ends of the spring arms were connected by two toggles pivoted together below the lower 20 ends of said arms, said toggles, in striking the bottom of the well would tend to spread apart and hold the spring arms apart. If the toggles were pivoted together and to the arms within their lower ends to hold the arms 25 against a tendency to spring inwardly and any obstruction should strike one of them both toggles would move upwardly at their inner pivoted ends and permit the spring arms to release the tiling with which the coupler 30 could not be again connected. Where the outer ends of such toggles form the shoulders on which the tiling rests as has been done heretofore, such projecting ends tend to chip the end of the tiling and there is a danger of such 35 ends being clamped between two tiling or tubing sections. All such dangers are obviated by having the spring arms free to spring apart at their lower shouldered ends and there loosely linked to the operating rod.

40 The disk C^2 cannot strike any obstruction when the coupler is being lowered as it is of less diameter than the circle described by the spring arms and the spacing projections or pins A^5 hold the coupler steady and concentric with the tiling section.

45 Having thus described my invention, what I claim as new, and desire to secure by Letters Patent of the United States, is—

1. A coupler of the character described comprising a body having a suspension device secured to its upper end, a series of depending outwardly inclined spring arms secured fixedly at their upper ends to the body and provided near their lower ends on their outer 50 sides with integral shoulders to support a tiling section and extending downwardly and inwardly toward each other from the said shoulders for the purpose described, and an operating rod separate and independent of 55 the said suspension device and linked to the lower ends of said springs to draw them toward each other but allowing them normally to spring apart, substantially as herein described.
- 60 65 2. A coupler for the purpose described com-

prising a body having a suspension device secured to its upper end, a series of spring arms extending through the grooves and below the body and secured at their upper ends to said body, shoulders on the lower diverging ends 70 of the arms, the said arms extending downwardly and inwardly toward each other from the said shoulders, an operating rod separate and independent of the said suspension device and extending down through the body 75 and linked to the lower extremities of the spring arms, and provided therebelow with a disk or head, by which it is automatically operated to move the arms inwardly to release the tile and a catch on the body to lock the 80 rod when moved upwardly, substantially as herein described.

3. A coupler comprising the body having external longitudinal grooves, the spring arms extending through the said grooves and having their upper ends bent over the upper face of the body, a band encircling the upper end of the body, and binding the arms thereto; the said spring arms diverging below the lower end of the body and then extending downwardly and inwardly; shoulders for the tiling being formed where the arms have their greatest divergence, an operating rod extending down through the body and linked to the lower extremities of the said spring arms, substantially as herein described.

4. A well tiling coupler, comprising a cylindrical body block A , having a suspension device on its upper end, a series of spring arms secured fixedly at their upper ends to the said block and bent outwardly below the block to form the tile-supporting shoulders and curved or inclined downwardly and inwardly therefrom, an operating rod extending down through the block and separate and independent of its suspension device, links connecting the rod and spring arms below the block, and pins projecting from the outer side of the block intermediate of the said spring arms, substantially as set forth.

5. A coupler for tiling consisting in the tapering cylindrical block having external longitudinal grooves deeper at their lower portions, a series of spring arms secured to the block at their upper ends and extending 105 through said grooves about flush with the outer face of the block, the lower ends of the arms being provided with shoulders and curved or inclined inwardly therebelow, a toothed operating rod extending down through the block and 110 connected between its ends with the lower extremities of the spring arms, and having a disk or head therebelow, substantially as herein described.
